ELECTRIC MULTIPLE SWITCHES

Francesco Tringali, Augusta, Italy

Application December 7, 1953, Serial No. 396,383

Claims priority, application Italy December 20, 1952

3 Claims. (Cl. 200—9)

Multiple switches normally used in radio apparatus (sliding contact switches) have some drawbacks due to their mechanical construction, which after a shorter or longer period of operation result in an increase of the electric resistance between the contacts, which might cause the total interruption of the current, especially if the current, flowing through the circuit including said contacts, is of a very high frequency (short waves).

Other types of similar switches, the drum switches, though being more reliable in operation, have the drawback of being cumbersome and expensive, and therefore are hardly or not at all employable in apparatus where the space is limited or where the economic factor is prevailing.

An object of this invention is to eliminate the mentioned disadvantages, by providing a switch of a type absolutely free from wrong contacts, having limited dimensions and being economical enough to substitute with advantage for the switches with sliding contacts.

This is possible because of a new arrangement and shape of the contacts and of a characteristic arrangement and shape of the contactors.

In the annexed drawings an embodiment of a multiple commutator in accordance with this invention is shown by way of example.

Fig. 1 is a plan view of a stator member included in a switch embodying the present invention;

Fig. 2 is a sectional view taken along the line II—II of Fig. 1;

Fig. 3 is an electrical diagram showing the various commutations obtainable with the switch illustrated in Figs. 1 and 2;

Fig. 4 is a plan view similar to Fig. 1, but showing another embodiment of the invention;

Fig. 5 is a sectional view taken along the line V—V of Fig. 4;

Fig. 6 is an electrical diagram showing the various commutations obtainable with the switch of Figs. 4 and 5.

Fig. 7 is a plan view of a rotor member to be used in connection with either of the stator members illustrated in Figs. 1 and 4, respectively;

Fig. 8 is a side elevational view of the rotor member of Fig. 7;

Fig. 9 is a sectional view taken along the line IX—IX of Fig. 7;

Fig. 10 is a side elevational view of a switch assembly made up of a plurality of the rotor and stator members illustrated in Figs. 1 to 9, inclusive;

Fig. 11 is a fragmentary side elevational view of a modified form of rotor contactor; and

Fig. 12 is a side elevational view, partly broken away and in section, of the rotor contactor of Fig. 11.

Referring to the drawings, Figs. 1, 2 and 3 illustrate an embodiment of the invention, wherein, a small plate 1 of insulating material, having the shape of a circular crown, has fixed thereon, radially extending metallic contacts 2 arranged with equal angular distances therebetween and with their ends 3 shaped in angular form to

2

define V-shaped notches. These ends 3 of the several contacts are lodged, by means of a slight bending, in corresponding cavities of rectangular or similar shape, suitably arranged along the inner border of the crown. In this manner the inner border 4 of the crown is formed of arcuate insulating lengths alternating with angular conducting cavities corresponding to the contacts themselves. The plate 1 is formed with holes 5, and suitable securing bolts can be extended through the latter and through perforated distancing blocks 6 to secure together two contact crowns of the described type which are spaced apart and form a pair of elements of the stator, and to secure together several of such pairs for forming the complete stator of the commutator.

The two small contact plates of each pair can be made in the form as above described, so as to realize the commutation according to the electric diagram of Figure 3; alternatively, the contacts of one of the small plates of each element may have another shape, as shown in Figs. 4 and 5, in order to obtain the commutation according to the electric diagram of Figure 6; or otherwise the two crowns forming each stator element may be made, if this should be practically convenient, by a single crown of insulating material having a suitable thickness, on which the two contact sets are fixed or incorporated along the opposed faces of the crown, with each set of contacts including an equal number of contacts at corresponding angular positions.

In the embodiment of Figs. 4, 5 and 6, a single circular metallic crown or several sectors 7 thereof, insulated with respect to each other, are fixed on the contact plate 8 made of insulating material, and each sector is provided with a terminal 9 and a suitable number of angular cavities or notches 10, arranged along the inner periphery, in radial and angular positions identical to the notches of the contacts of the other set (not shown) with which it forms a couple.

It is evident that the number of the sectors determines the number of different circuits controllable by the switch, whereas the number of the angular cavities of each sector determines the number of the positions or commutations of the switch.

It is also evident that, by suitably joining several elements (pairs) the number of the commutable ways, as well as the number of the positions, can be increased at will, as shown on Figure 10.

Figs. 7, 8 and 9 show a rotor element of the switch, consisting of a cylindrical body of insulating material 11 in which there are radial channels 12, containing cylindrical contacting rollers 13 and pressure springs 14, which press the corresponding rollers in a radially outward direction.

The rotor element 11 is fixed by means of suitable members in a concentric position in respect to the stator element and can turn with its axle 15, on which it is fixed, within the crowns of the stator element, as shown on Figure 10.

A rotatory movement imparted to the axle 15, produces the step-by-step rotatory movement of the rotor, which is successively stopped in exact correspondence to the angular cavities (stopping notches) of the several contacts, owing to the rollers 13 entering the corresponding notches under the pressure of the springs, so progressively establishing at each snapping one or more contact bridges (according to the number of contactors contained in the rotor) between the corresponding contacts of the two small plates of each stator pair. Owing to the radially outward force continuously exerted by the springs on the contacting roller, and owing also to the particular shape of the angular notches of the several contacts and to the shape of the contacts, the engagement between the roller 13 and the contacts is always reliable, even after a

long time of use, with an electric contact resistance practically neglectable.

Obviously, the number of the contactors of each rotor element is determined by the number of the sectors or ways of the stator element, and it is possible to couple on the same rotation axle several identical rotor elements in correspondence of a same number of stator elements, also identical, in order to increase the number of the ways and of the positions of the switch according to Figure 10.

According to a further form of realization, shown on Figs. 11 and 12, the contactors can have the shape of rectangular metallic bodies 16 having a suitable thickness and round outside edges for engagement with the contacts of the stator 17, and which are held in radial guides 18 on the rotor and forced in a centrifugal direction against the surrounding contacts of the rotor by means of springs 19.

Of course, the shape and the particulars of construction can be modified in accordance with the practical requirements, without departing from the scope of the invention.

I claim:

1. A multiple switch for the commutation of radio frequency electrical currents, said switch comprising at least one stator member and a coaxial rotor member associated with each stator member, said stator member including at least two thin annular members of insulating material in axially spaced apart relation to provide an air gap therebetween, a plurality of blade contacts fixed on each of said annular members, each of said blade contacts having at least one radially inward opening V-shaped notch axially aligned with a corresponding

5 notch of a blade contact on another of said annular members, and said rotor member including a body of insulating material having at least one radial guideway therein, a solid cylindrical bridging contact having a uniform cross-sectional area along its entire length and arranged in said guideway with its axis parallel to that of said rotor body and spring means urging said bridging contact radially outward into corresponding V-shaped notches of blade contacts on said annular members of the stator to provide electrical contact between the blade contacts

10 separated by said air gap.

2. A multiple switch for the commutation of radio frequency electrical currents as in claim 1; wherein each stator further includes insulating spacing members holding said annular members in axially spaced relation.

15 3. A multiple switch for the commutation of radio frequency electrical currents as in claim 1; wherein each of said blade contacts is a thin elongated conducting member arranged radially and having a fishtail-shaped radially inward end defining said V-shaped notch.
